CLAIM

The ornamental design for a display screen with graphical user interface, as shown and described.

DESCRIPTION

FIG. 1 is a front view of a display screen with graphical user interface showing a first embodiment of the claimed design; FIG. 2 is a second embodiment thereof; FIG. 3 is a third embodiment thereof; FIG. 4 is a fourth embodiment thereof; FIG. 5 is a fifth embodiment thereof; FIG. 6 is a sixth embodiment thereof; FIG. 7 is a seventh embodiment thereof; FIG. 8 is an eighth embodiment thereof; FIG. 9 is a ninth embodiment thereof; and, FIG. 10 is a tenth embodiment thereof.

The horizontal broken lines in FIGS. 2, 3, 5, 7, 8 and 10, which are enclosed within a solid line border, form part of the claimed design. The broken line showing portions of an electronic device illustrates environment and forms no part of the claimed design. The rectangular broken line showing the display screen illustrates portions of the article and forms no part of the claimed design.
